UNITED STATES PATENT OFFICE

ARTHUR SHAW, OF HANLEY, COUNTY OF STAFFORD, ENGLAND, ASSIGNOR
TO THE J. L. MOTT IRON WORKS, OF NEW YORK, N. Y.

DESIGN FOR A BOWL AND TRAP FOR WATER-CLOSETS.

SPECIFICATION forming part of Design No. 16,356, dated October 27, 1885.

Application filed August 22, 1885. Serial No. 175,116. Term of patent 7 years.

To all whom it may concern:

Be it known that I, ARTHUR SHAW, of Hanley, county of Stafford, England, have invented a new Design for Bowls and Traps 5 for Water-Closets, of which the following is a specification.

This design is represented in the accompanying photograph, the leading feature of which is the dolphin's head upon the trap at 10 the junction with the ribbed bowl. The bowl is ribbed upon the exterior surface, as at A, and these ribs converge toward the delivery pipe, and the delivery pipe and trap on the outside represent a dolphin's head, B, and body, 15 C, as shown in the photograph, the outlet portion of the bowl appearing as if it passed into

the dolphin's mouth, D. At the junction of the ornamental floor-flange E and the discharge-pipe are leaflet ornaments F.

I claim as my invention—

The design for the shape and ornamentation of the bowl and trap, consisting in ribs upon the exterior of the bowl and a dolphin's head and body upon the exterior of the delivery-pipe and trap, substantially as described 25 and shown.

Signed by me this 1st day of August, A. D. 1885.

ARTHUR SHAW.
